UNITED STATES PATENT OFFICE

2,093,150

CLOCK

Gideon Lemata, Los Angeles, Calif.

Application June 1, 1936, Serial No. 82,732

9 Claims.

(Cl. 58—50)

My invention relates to clocks and more particularly to illuminated dials for clocks.

An important object of my invention is to provide means for casting variegated lights upon a translucent dial for a clock.

Another object is to provide means for casting an extremely large number of colors and color combinations upon the rear face of a ground glass clock dial.

10 Further objects reside in the provision of efficient mechanism for reflecting or transmitting such variegated lights.

The invention also comprises novel details of construction and novel combinations and arrangements of parts, which will more fully appear in the course of the following description.

In the drawings, like reference characters designate similar parts in the several views.

Figure 1 is an elevation of mechanism embodying the features of my invention, showing the housing in section.

Figure 2 is a section taken on the line 2—2 of Figure 1.

Figure 3 is a section taken on the line 3—3 of Figure 2.

Figure 4 is a section taken on the line 4—4 of Figure 1. In Figure 4, a housing for the mechanism has been removed.

Figure 5 is a plan view of a disc having differently colored segments of art glass, comprised in the invention.

Fig. 6 is a detail perspective view of an envelope which comprises support means for certain mirrors.

35 Fig. 7 is a detail perspective view of a multi-bladed paddle with reflecting surfaces.

Referring more in detail to the drawings, the reference numeral 6 generally designates a housing for the invention. A platform 7 rests on the bottom of the housing. The housing has an opening 8 at the front face of the housing, whereby to expose a ground glass dial 9. It is to be understood that the dial 9 is any desired clock dial.

45 Disposed behind the dial is a system or cage of flat mirrors, consisting of mirrors 10 and 12 angularly arranged and providing wall members of a mirrored space 15. A mirror 13 lying on the platform provides the floor of said space and a mirror 14 acts as a top plate for the space 15. The ground glass dial 9 forms a translucent face for the mirrored space.

Angularly arranged braces 16 on the platform 7, together with upright members 17 and an envelope 18, maintain the mirrors in position. The

envelope 18 comprises upright members 81 and 82 that have flanges 83 providing feet. The envelope likewise has a top member 84 bridging the space between the upright members 81 and 82, as perhaps best shown in Figure 6. The upright members 17, which are at either side of the opening 8, also provide abutments for the ground glass dial. The top mirror 14 has an aperture 19 for admitting illumination to the mirrored space 15. It is to be understood in this description and in the hereunto appended claims that an equivalent for the aperture 19 would be a break in the silvering of one of the mirrors. A shutter 20, pivotally mounted upon a standard 18, is arranged to close or open the aperture 19. The lower end of the standard 18 is notched, as shown at 178, whereby the standard is fastened to a block 179 on the platform 7. The shutter is manually operated by a knob 21 disposed exteriorly of the housing. The knob 21 is fastened on a shaft 22, which, through the engagement of a bent pin 23 on the shaft 22, together with a slot 24 on an arm 25, 10 operates the shutter 20. The arm 25 is of course rigidly mounted relative to the shutter. A sleeve 26 on a bracket 27 rotatably supports the shaft 20. 15

Figure 2 is a section taken on the line 2—2 of Figure 1.

Figure 3 is a section taken on the line 3—3 of Figure 2.

Figure 4 is a section taken on the line 4—4 of Figure 1. In Figure 4, a housing for the mechanism has been removed.

Figure 5 is a plan view of a disc having differently colored segments of art glass, comprised in the invention.

Fig. 6 is a detail perspective view of an envelope which comprises support means for certain mirrors.

Fig. 7 is a detail perspective view of a multi-bladed paddle with reflecting surfaces.

Referring more in detail to the drawings, the reference numeral 6 generally designates a housing for the invention. A platform 7 rests on the bottom of the housing. The housing has an opening 8 at the front face of the housing, whereby to expose a ground glass dial 9. It is to be understood that the dial 9 is any desired clock dial.

45 Disposed behind the dial is a system or cage of flat mirrors, consisting of mirrors 10 and 12 angularly arranged and providing wall members of a mirrored space 15. A mirror 13 lying on the platform provides the floor of said space and a mirror 14 acts as a top plate for the space 15. The ground glass dial 9 forms a translucent face for the mirrored space.

Angularly arranged braces 16 on the platform 7, together with upright members 17 and an envelope 18, maintain the mirrors in position. The

envelope 18 comprises upright members 81 and 82 that have flanges 83 providing feet. The envelope likewise has a top member 84 bridging the space between the upright members 81 and 82, as perhaps best shown in Figure 6. The upright members 17, which are at either side of the opening 8, also provide abutments for the ground glass dial. The top mirror 14 has an aperture 19 for admitting illumination to the mirrored space 15. It is to be understood in this description and in the hereunto appended claims that an equivalent for the aperture 19 would be a break in the silvering of one of the mirrors. A shutter 20, pivotally mounted upon a standard 18, is arranged to close or open the aperture 19. The lower end of the standard 18 is notched, as shown at 178, whereby the standard is fastened to a block 179 on the platform 7. The shutter is manually operated by a knob 21 disposed exteriorly of the housing. The knob 21 is fastened on a shaft 22, which, through the engagement of a bent pin 23 on the shaft 22, together with a slot 24 on an arm 25, 10 operates the shutter 20. The arm 25 is of course rigidly mounted relative to the shutter. A sleeve 26 on a bracket 27 rotatably supports the shaft 20. 15

A spindle 28 mounted in a thrust bearing 29 and in a bearing 30 carries a disc 31 consisting of a circumferential series of colored art glass segments 32. A bolted hub 33 mounts the segments of the disc on the spindle 28. The segments of the disc are disposed to revolve in a path over the aperture 19 in the top mirror. The bearings 29 and 30 are mounted upon the standard 18. 20

A reflector light 34 is pivotally mounted above the disc 31, and is mounted directly above the aperture 19, whereby light shining through the segments of the art glass disc will pass through the aperture 19 and into the mirrored space 15. 25 A transformer 35 is employed for stepping down ordinary commercial voltage to provide current of small voltage for the light 34. The light 34 depends from an arm 70 that is pivotally mounted in a sleeve 71, which sleeve is in turn supported upon a standard 72 by means of hook-shaped bolts 73. The hook shape of the hooks is perhaps best shown in plan in Figure 4. Wires 74 and 75 lead from the transformer 35 to the light 34. 30 It is to be understood that the sleeve 71 and the arm 70 act as conduits for the wires 74 and 75. A manual switch 36 is arranged in the wiring 37 for the transformer. A cable 38 having wires 39 and 40 leading to and from a source 35

(not shown) complete the circuit for the transformer.

Rotatable in the space 15 is a multi-bladed paddle 41 having reflective surfaces, e. g., of polished chromium. The paddle preferably has radial blades 42 and 43 disposed longitudinally of its hollow shaft 44. Ends of the blades 42 and 43 are inclined away from the shaft, as best shown in Figure 1. The blade 42 has a curved tip at one end, as indicated at 45, and both of blades 42 and 43 have curved tips at the opposite end, as indicated at 46. The hollow shaft 44 is mounted upon a hollow drive shaft 16. The shaft 16 extends through a circular opening 17 cut in abutting edges of the mirrors 10 and 12.

Also disposed radially on the hollow shaft 44 at quadrant points from the blades 42 and 43 are smaller blades or fins 47 and 48. The fins preferably have angularly arranged sides, and the tips of the sides may be bent outwardly slightly, as shown at 49. It will be noted that the curves and dips of the paddle blades and fins provide a plurality of differently disposed reflecting surfaces. The paddle rotates substantially in the plane of the light that passes through the art glass and through the aperture 19.

The invention also comprises an electric clock mechanism 50 in combination with the features hereinbefore described. Since the electric clock mechanism may be of any conventional construction and since it is not claimed per se, further illustration and description of same appear unnecessary. Suffice to say that a second-hand 51, a minute-hand 52 and an hour-hand 53 are driven by the electric clock mechanism 50 in a plane between the mirrored space 15 and the ground glass dial 9.

Operatively connected with the electric clock mechanism 50 is a train of gears 54 which drive pulleys 55 and 56. A pulley 57 is mounted on the hollow shaft 16. (The hollow shaft 16 contains the conventional driving shaft and driving sleeves of the second-, minute- and hour-hands.) A belt 58 drives the pulley 57 from the pulley 56 at a slow rate of rotation.

A counter shaft 59, mounted on a standard 80, carries two sheaves 60 and 61, and the spindle 28 carries graduated sheaves 62. A belt 63 is passed around the pulley 55, over the sheaves 60 and 61 and around a selected one of the sheaves 62. By moving the belt from one of the sheaves 62 to the other, the art glass disc 31 may be rotated at different rates. If desired, the belts 58 and 63 may be of coiled springs, to provide even tension at all times. A brace block 180, which is mounted on the platform 7, has notched ends, as shown at 181 and 182, in which notches are fastened the lower ends of the standards 72 and 80.

Wires 64 and 65 connect the clock mechanism 50 in the circuit provided by the wires 39 and 40. The light 34 and the clock mechanism are connected in parallel, whereby the lighting effects may be turned off and still allow the clock to operate.

In the operation of my invention, the cable 38 is plugged into an ordinary light socket, which provides current for operating the electric clock mechanism and for the illuminating mechanism.

The hands of the clock are visible at all times behind the ground glass face 9, and it is preferable to allow the clock to operate continuously. When it is desired to turn on the lighting effects, the switch 36 is closed. The light 34 is thereby illuminated, which casts colored lights upon the reflecting paddle 41 and the bottom mirror 13,

through the intermediary of the art glass disc.

It is to be understood that adjacent segments 32 of the disc 31 are of different colors, so that as the disc 31 slowly rotates, a wide variety of attractive lights are cast into the mirrored space 15.

Rotation of the paddle 41 reflects the lights upon the various mirrors around the space 15, and pleasing, variegated lights are cast upon the ground glass dial 9. When it is desired to dim the lights, the control 21 is manipulated.

While I have illustrated and described what I now regard as the preferred embodiment of my invention, the construction is, of course, subject to modifications without departing from the spirit 15 of my invention. I, therefore, do not wish to restrict myself to the particular form of construction illustrated and described, but desire to avail myself of all modifications which may fall within the scope of the appended claims.

Having thus described my invention, what I claim and desire to secure by Letters Patent is:

1. In a clock, a translucent dial, mirror means behind and disposed to reflect light upon the dial, a rotary paddle disposed between the mirror means and the dial and having reflective surfaces disposed to reflect light upon the dial and upon the mirror means, a source of light, a rotary disc composed of segments of differently colored glass disposed to move in a path between the source of light and the paddle, and means to rotate the paddle and the disc.

2. In a clock, a translucent dial, mirror means defining a space behind and disposed to reflect light upon the dial, a paddle having reflective surfaces mounted to rotate in the mirrored space, a source of light, a rotary disc comprised of segments of differently colored glass disposed to rotate in a path between the source of light and the paddle, and means to rotate the paddle and the disc.

3. In a clock, a translucent dial, movable means disposed behind the dial and having a reflective surface arranged in one position to reflect light upon the dial, mechanism to actuate said means, and means to cast differently colored lights upon said moving means.

4. In a clock, a translucent dial, hands to traverse the dial, concentric spindles for the hands, a hollow shaft concentric with said spindles, a reflective blade on the hollow shaft, means to rotate the hollow shaft, mirror means disposed to reflect light from the blade upon the dial, and means to cast colored lights upon the blade.

5. In a clock, a translucent dial, mirrors arranged in V-shaped formation behind the dial, top and bottom mirrors, together with the first-mentioned mirrors, forming a closed, mirrored space behind and reflecting upon the dial, there being an opening in the mirror means for admitting light, a rotary element comprising a series of differently colored segments of glass, a rotary, reflecting element in the mirrored space, a source of light arranged to cast light through the colored segments, through said opening and upon the rotary, reflecting element, and means to rotate the two said rotary elements.

6. In a clock, a translucent dial, a rotary element having reflective blade means behind the dial, mechanism to cast differently colored lights upon the reflective blade means, including a moving series of differently colored segments, a source of light arranged to illuminate the segments successively, means to rotate the rotary element, and means to move said series of segments.

7. In a clock, a translucent dial, mirrors defining a space behind the dial, there being an opening in the mirrors for admitting light, a manually operable shutter controlling the light passing through said opening, a rotary, reflecting element in said space, a rotary member having a series of differently colored segments arranged to pass said opening successively in the rotation of said member, a source of light arranged to illuminate the segments as they pass the opening, and means to rotate said element and said member.
8. In a clock, a translucent dial, a rotary element having a curved, reflective blade behind the dial, mechanism to cast differently colored lights

upon the curve of the reflective blade, the mechanism including a series of differently colored members, a source of light arranged to illuminate the members successively, and means to rotate said element.

9. In a clock, a translucent dial, a rotary element having angularly arranged blade means behind the dial, mechanism to successively cast differently colored lights upon the angularly arranged blade means, the mechanism including a series of differently colored members, a source of light arranged to illuminate the members successively, and means to rotate said element.

GIDEON LEMATA. 15
